[57] CLAIM

The ornamental design for a combined cartridge or cassette recorder and player, as shown in the drawings.

DESCRIPTION

FIG. 1 is a front, top and right side perspective view of a combined cartridge recorder and player showing my new design;

FIG. 2 is a front elevational view;

FIG. 3 is a rear elevational view;

FIG. 4 is a left side elevational view;

FIG. 5 is a top plan view;

FIG. 6 is a bottom plan view; and

FIG. 7 is a view similar to FIG. 1 with the speaker cabinets shown in extended position.
